MOTOR DRIVEN SWITCH MECHANISM

Georg Ogurkowski, Zug, Switzerland, assignor to
Landis & Gyr, A-G., a limited joint-stock com-
pany, Zug, Switzerland

Application May 24, 1928, Serial No. 280,312
In Switzerland June 11, 1927

1 Claim. (Cl. 200—92)

The invention relates to new and useful improvements in motor-driven switch operating mechanisms, and more especially to novel and useful improvements in powerful, compact and reliable mechanisms of the kind described which are especially adapted to be mounted within the housings of clocks, meters or other switch-controlled mechanisms.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, construction, arrangements combinations and improvements herein shown and described.

The accompanying drawings, referred to herein and constituting a part hereof, illustrate one embodiment of the invention, and together with the description, serve to explain the principles of the invention.

Of the drawing:

Fig. 1 is a top plan of a mechanism embodying the invention;

Fig. 2 is a side elevation looking at Fig. 1 from the top of the sheet; with certain parts shown in outline only, and with the front frame plate removed, for the sake of clearness.

Fig. 3 is a fragmentary horizontal section, taken on the line 3—3 of Fig. 2, with certain parts omitted; and

Fig. 4 is a vertical transverse fragmentary section taken substantially on the line 4—4 of Fig. 1.

Referring now in detail to the embodiment of the invention illustrated by way of example in the accompanying drawing, a pair of parallelly arranged side plates 1 and 2 constitute a supporting frame for the mechanism, and these plates are held in place by a plurality of spacing and binding rods 3, 4, and 5. The switch-actuating motor may be of any known and suitable form, but as preferably embodied herewith, an induction motor is provided having a field coil 10 and field poles 11 and 12 formed on a core 9. The core 9 comprising the poles 11 and 12 is mounted on the frame plate 2 by suitable means, such as a plurality of spacing studs 13, and a plurality of clamping or holding screws 14. The rotor 17 of the induction motor has its shaft 18 journaled in supports 19 and 20, fixed on the respective side plates 1 and 2 of the switch mechanism.

Mechanism is provided for very greatly reducing the speed between the rotor shaft 18 and the switch-actuating devices, and as embodied, a pinion 23 is fixed on rotor shaft 18, said pinion meshing with a gear 24, fixed on a shaft 25, journaled in the side plates 1 and 2. Fixed also on shaft 25 is a pinion 26, which meshes with a gear wheel 27, fixed on a shaft 28, which shaft is likewise journaled in the frame plates 1 and 2. Fixed also on a shaft 28 is a ratchet wheel 30, with which cooperates a pawl 31, pivoted at 32 on the frame, and which is acted on by a spring 33. This prevents any backward movement of the mechanism. Fixed on shaft 28 is a pinion 38, which meshes with a gear wheel 39, later to be described.

In accordance with certain features of the invention, the driving motor is utilized to wind a spring-operated mechanism, the spring-operated mechanism in turn under the control of delayed-operation devices serving to actuate the controlled switch mechanism. The mechanism as exemplified operates also to open the controlled switch on one cycle and to close it on the next. Means are likewise provided by the invention for automatically stopping the driving motor after a single actuation of the switch mechanism, and as embodied, said mechanism cooperates with, and is structurally interconnected with, the spring-driven switch-actuating devices. In the present preferred embodiment of said means, the gear wheel 39 is formed on a cylindrical casing 40 within which is a flat coiled spring 41. The outer end of spring 41 is fixed to the interior of the casing 40, and the inner end thereof is fixed to a hub 42, which hub is fixed to a shaft 43, journaled in the side frames 1 and 2 of the mechanism. Fixed to the open side of cylinder 40, by suitable means such as screws 47, is a disk-like plate or closure 48, having a hub 49, eccentrically and loosely mounted on the shaft 43.

The delayed action starting and stopping means for the spring acting switch-actuating mechanism, comprises a two-armed lever 57, with its arms 58 and 59 preferably a quadrant apart. The lever arms are fixed to a hub 60, which hub is loosely mounted on the eccentric hub 49 of the casing for the spring 41. Means for effecting a spring buffer action in the stop mechanism is preferably provided, and accordingly a spring 61 has its inner end seated in a notch 62 in the hub 60, and has its outer end pressing against a pin 63, projecting laterally from the side of a lever 64, which lever is fixed on the shaft 43.

The arm 58, by reason of the loose mounting of the hub of the lever 57 on the eccentric hub 49 is movable longitudinally to permit and angularly to stop rotation of the shaft 43. It also operates alternately with flat faces formed in the sides of stop pins 69 and 70, fixed in and projecting from side plate 2 of the machine. The lever arm 64 (which is fixed on shaft 43) has its outer end shaped to cooperate with a switch control for starting and stopping the motor, as will now be described. The embodied form of said mechanism comprises devices, interposed in the power circuit of the motor, and including a contact carrying plate or arm which is engaged and moved by the arm 64 to break said power circuit and thereby stop the motor, and also on a sequential reverse movement of said contact carrying plate or arm on the next subsequent cycle of the mechanism, to similarly break the power circuit and again stop the motor.

Referring now in detail to the embodiment of the said automatically-operated stopping means in the motor circuit, a supporting plate 75 extends transversely between and is mounted on the frame plates 1 and 2. On this supporting cross plate 75 is mounted a block of insulating material 76, which carries three conducting plates 77, 78 and 79, which plates are each formed at an end thereof with corresponding circuit terminals 80, 81 and 82. The plate 77 has a contact piece 87 on which the plate 78 is seated by means of a spring 88. A bar 89 of insulating material, a contact piece 90, and the plate 78 carries a spring 91 provided with a contact piece 92. The parts 81, 82, 89, 90, 91 and 92 form an auxiliary switch for the motor operating in the manner already described. The contacts 87 and 92 may be in parallel in the motor power circuit and the contact 90 is alternately in closing circuit with these on successive cycles of the mechanism, and in each intervening movement breaks the circuit and stops the motor.

The contact carrying bar or plate 89 has its outer end in the path of movement of the arm 64 (which is fixed on shaft 43), so as to be engaged, moved and held by the latter on one cycle of the mechanism as shown in broken lines in Fig. 4. When on the next succeeding cycle arm 64 moves on and releases bar 89, the contact piece 90 then moves against the contact piece 87. The motor circuit is thus momentarily broken during the movement of bar 89, thereby stopping the motor. The circuit is again made however when contacts 87 and 90 are made, and the main switch can again start the motor.

Referring now to the embodied form of an actuated switch in any controlled circuit (such as that of a clock or relay) and connections whereby the actuating devices of the present invention move said actuated switch, an arm 101 is fixed to an exterior end of the shaft 43 outside the frame plate 2. Fixed to arm 101 is a pin 102 which projects through an elongated slot in a lever arm 103. Lever arm 103 is pivoted at 104 to the outer end of a lever 105, which in turn is pivoted at 106. Fixed with the other end of the lever 105 is laterally-projecting actuating arm 107. This arm is adapted to engage with and to move a bent spring 108 carrying a contact 109 adapted to cooperate with a fixed contact 110, to open and close the controlled circuit for a clock, relay or other device. The stop mechanism previously described is adapted, on successive cycles, to impart a semi-rotation to shaft 43, by reason of the arm 58 en-

gaging successively with the stop pins 69 and 70. It will be seen that on one semi-rotation of shaft 43, considered as starting from the position of Fig. 4, the controlled switch terminals 109 and 110 will be opened. On a successive semi-rotation of shaft 43 (bringing it back to the position shown in Fig. 4) the switch terminals 109 and 110 of the controlled circuit will be again closed as shown in said figure.

In the operation of the mechanism as described the main control switch for the motor is not shown, but may be either manually operated or automatically operated by a clock mechanism or otherwise. When the main controlling switch for the motor driving circuit is closed (the mechanism being considered as in the position shown in Fig. 4) the motor through the pinion and gear train described rotates the gear 39, and thereby winds up the spring 41. There is however, no motion of the shaft 43 due to the arm 64 being held by the spring 61 to the arm 59 of stop lever 57, which latter is held by the stop pin 69.

However, due to the rotation of the cylindrical housing 40 with the gear 39, eccentric hub 49 is rotated on shaft 43, and while spring 41 is being placed under greater tension due to the rotation of gear 39, arm 58 is gradually being withdrawn longitudinally from behind stop pin 69 due to the rotation of the eccentric hub 49 upon which the arm is mounted. When arm 58 is thus released from stop pin 69, it immediately makes a half-revolution, at the same time rotating upon the eccentric bushing or hub 49 (which has made a half revolution) and arm 58 therefore moves outward longitudinally and is then stopped by stop pin 70, as shown in broken lines in Fig. 4. This has permitted shaft 43 and arm 64 to make a concurrent half revolution under the impulsion of the spring 41, and arm 64 comes to rest in the broken line position shown in Fig. 4. The actuation of the controlled switch 109, 110 during each half revolution of shaft 43 has already been described. In this position it has engaged and moved the bar or plate from the solid to the broken line position of Fig. 4, thereby breaking the motor circuit during said movement and stopping the motor.

Thus when the main motor switch is thrown again, by hand or by any suitable automatic control, and the motor thereby started, the cycle of operations already described will again take place, however with the parts a half-rotation ahead, and with the stop mechanism starting from the position shown in broken lines in Fig. 4. During the consequent rotation of gear wheel 39, spring 41 will be put under tension, and the eccentric hub 49, rotating with gear wheel 39, will after a half revolution, retract and release stop arm 58 from stop pin 70, and arm 64 rotating from the broken line to the solid line position of Fig. 4 will release the bar or plate, and will break the circuit for the motor, thereby stopping it. Stop arm 58, now rotating on eccentric hub 49 will be radially projected, and will again be stopped by stop pin 69, and the control circuit contact 109 and 110 will be closed.

The invention in its broader aspects is not limited to the specific mechanism shown and described but departures may be made therefrom within the scope of the accompanying claim without departing from the principles of the invention and without sacrificing its chief advantages.

What I claim is:—

Switching mechanism including in combination side frames, a shaft rotatably mounted in said frames to be driven by a motor mounted between said frames, stop pins on one side frame, a stop arm mounted eccentrically on said shaft, a spring connected to said arm and shaft to

drive said arm from said shaft, a switch and operating means therefor controlled by said arm, said switch and operating means being positioned between said frames and between said shaft and motor.
